UNITED STATES PATENT OFFICE.

WILLIAM BETTMANN, OF NEW YORK, N. Y., ASSIGNOR TO RESTORFF & BETTMANN, OF SAME PLACE.

DESIGN FOR A BOTTLE-CASE.

SPECIFICATION forming part of Design No. 19,088, dated May 14, 1889.

Application filed October 18, 1888. Serial No. 288,470. Term of patent 14 years.

To all whom it may concern:

Be it known that I, WILLIAM BETTMANN, of the city of New York, in the county and State of New York, have invented and produced a new and original Design for Cases for Bottles, of which the following is a specification.

This invention relates to a design for a bottle-case, such as those used in putting up dressing for ladies' shoes.

10 The accompanying drawing represents a bottle-case in elevation embodying this design, a portion of the cover of said case being broken out, showing the screw-threaded neck of the body over which said cover fits.

15 The leading features of this design are a body cylindrical in shape and having a surface ornamentation, as shown and herein-after described, and a cover comprising a cylinder and a dome-like knobbed top having 20 surface ornamentations, as shown and herein-after described.

In the drawing, A represents the body, and B the cover. The body A is a cylinder in form, provided at its bottom with a torus, B, and above said torus with a concave bead, B'. The cover D is in the shape of a smaller cyl-

inder surmounted by a dome-like top, D', having a knob-shaped device, E, and is provided with a square bead, B², between its cylinder and top, and at its lower end with a conical bead, D³, an oval bead, D⁴, and between said last-mentioned beads with a torus, C.

I claim—

The design herein described and shown, the same consisting of a torus, a concave bead above said torus, a vertical cylinder above the concave bead, an oval bead above the vertical cylinder, a torus above the oval bead, a conical bead above the upper torus, a smaller vertical cylinder above the conical bead, a square bead above the smaller vertical cylinder, a dome-like top above said square bead, and a knob-shaped device surmounting said dome-like top.

In testimony that I claim the foregoing as my invention I have signed my name in presence of two subscribing witnesses.

WILLIAM BETTMANN.
